UNITED STATES PATENT OFFICE.

JOHN M. HOWARTH, OF WAUSAU, WISCONSIN.

MACHINE AND PROCESS FOR PULLING CANDY.

1,214,465.

Specification of Letters Patent.

Patented Jan. 30, 1917.

Application filed December 16, 1915, Serial No. 67,224. Renewed September 22, 1916. Serial No. 121,692.

To all whom it may concern:

Be it known that I, JOHN M. HOWARTH, a citizen of the United States, residing at Wausau, in the county of Marathon and State of Wisconsin, have invented a new and useful Improvement in Machines and Processes for Pulling Candy, of which the following is a specification.

My invention relates to an improved device for stretching or pulling certain kinds of candy and consists in the constructions, arrangements and combinations of parts herein described and claimed.

Among the objects of my invention is to provide a machine which shall be capable of pulling certain kinds of candy which require a certain amount of working before reaching a state from which they will readily harden.

Other objects and advantages will appear in the following specification reference being made to the accompanying drawings in which—

Figure 1 is a perspective view of the device showing the machine as in operation. Fig. 2 is a cross section on the line 2—2 on Fig. 1. Fig. 3 is a detail cross section on line 3—3 on Fig. 1. Figs. 4 to 9 inclusive are diagrammatic views illustrating the action on a batch of candy during one complete pulling operation.

In the drawings, 1 represents a bed-plate which is supported by legs 2 which are secured to the bed-plate at each end. Mounted on one end of the bed-plate is a standard 3 which is formed with a bearing boss 4 at the top and bottom as shown, a third bearing boss 5 being located midway of the upper and lower bosses for the support of the oscillator shaft 6.

An oscillator bar 7 is secured to the front end of the shaft 6 and pins 8 and 9 are in turn secured to the opposite ends of the bar 7 from whence they project forwardly and receive and hold the candy batch. The bar 7 is oscillated through the medium of a pinion 10 which is secured to the rear end of the shaft 6.

A shaft 11 is located in the lower boss 4 and is supported near its front end by a bearing 12, a crank 13 being secured to the front end of the shaft 11. An arm 14 is loosely mounted on the shaft 11 just behind the standard 3, the arm having a gear segment 15 at its upper end the gear segment

meshing with the pinion 10 and imparting movement to the pinion when the arm 14 is moved. A pitman 16 connects the lower end of the arm 14 with a crank 17 on a driven shaft 18 which is mounted in depending bearings 19 at the opposite end of the bed-plate 1, as shown in Figs. 1 and 3. A drive shaft 20 is mounted above the shaft 18 in other bearings on the bed-plate 1 and an operating crank 21 is removably attached to the end of the shaft 20 so that it may be turned to operate the device. While I have illustrated a crank for manually operating the machine, it will be understood that in practice a motor will be connected with the shaft 20.

A pinion 22 on the drive shaft 20 meshes with a gear 23 on the driven shaft 18. A crank 24 is also mounted on the front end of the driven shaft 18 and a pitman 25 is connected to the ends of the crank 24 on the shaft 18 and 13 on the shaft 11 so that an oscillatory or pendulous motion is imparted to the shaft 11 as the shaft 18 rotates. An arm 26 is secured to the shaft 11 close to the bearing 12 and a pin 27 projects inwardly from the upper end of the arm 26 on which the pin is mounted.

A shaft 28 is located in the top bearing boss 4 as shown in Fig. 2, a crank 29 being secured to the rear end of the shaft. A connecting rod 30 joins the crank 29 with a similar crank 31 on the shaft 11 so that the pendulous motion of the shaft 11 will be imparted to the shaft 28. The shaft 28 extends forwardly and bends downwardly then inwardly to form a finger or pin 32 similar to 27.

The shafts 11 and 28, their pins 27 and 32 and the cranks 31 and 29 are virtually bell-crank which are placed in such positions on the standard 3 that the pins 27 and 32 will occupy opposite positions at each side of the standard when the bell cranks are at the limits of their movements. The connection 30 causes the bell-cranks to move together but since the pins of the bell cranks are positioned oppositely of the center of the standard 3, the pins will be caused to move in opposite directions. At the same time 105 the pins 8 and 9 on the bar 7 are performing a part of their oscillatory strokes and the result is a stretching of the candy imposed on the pins.

Having thus described the mechanism of 110

the device, the operation thereof is as follows:—Let it be assumed that a batch of candy has been placed in position on the pins 8 and 9 of the oscillating bar 7. This is done when bar 7 is substantially horizontal as in Fig. 5, the pins 27 and 32 being out of the way at such a time. The first four steps will be as shown in Figs. 6, 7, 8, and 9 and during this part of the operation the pins 32 and 27 will have crossed the path of the pins 8 and 9 and taken up the candy batch. The next position would be as in Fig. 4 from which the description of the pulling process, will commence. At this time the candy forms a reversed letter Z as shown in Fig. 4, from which it will be observed, the bar 7 is at one limit of its movement and just about to move as indicated by the arrow. The pins 32 and 27 have yet a small distance to travel causing the candy to be stretched still farther. When the bell-crank pins 32 and 27 reach the limits of their movements as in Fig. 5, the oscillating pins 8 and 9 will have moved to such a position as to bring the candy batch together. The bell-cranks now reverse and start in opposite directions which are the same directions as those of the pins 8 and 9 as shown in Fig. 6. When this position is reached the pins 32 and 27 will fold the outer portions of the batch under the pins 8 and 9 these pins now being near the place of reversal which is shown in Fig. 7. As the pins 8 and 9 start back the pins 32 and 27 still continue their movement since they have not completed their outward travel and thus the second stretching process commences. Since the pins 8 and 9 now travel away from the pins 32 and 27 as in Fig. 8 the candy will be pulled into the shape of a letter Z and when the pins 8 and 9 reach their first positions the candy batch will be brought together again as in Fig. 9. The pulling process is now repeated but the parts will move in opposite directions from those mentioned in the foregoing description.

The co-acting pins 8 and 32 and 9 and 27 each describe a numeral 8 in the movements just described and I have found that by fastening a cord to one pin and extending the long end over the other, then making a one-half revolution of the bar 7, that twenty-three inches of string are used.

While the structure shown embodies preferred constructions, obviously variations and modifications may be made without departing from the spirit of the invention or the scope of the claims.

I claim:—

1. In a candy pulling machine; an oscillating arm having pins on opposite sides of its axis of motion, bell-cranks located on axes above and below that of the oscillating arm, pins carried by the bell-cranks and being adapted to move in opposite directions

across the paths of movement of the oscillating arm pins, and means for moving the bell-cranks and oscillating arm simultaneously, all combined substantially as described.

2. In a candy pulling machine; an oscillating arm having pins on opposite sides of its axis of motion and parallel therewith, bell-cranks located above and below the oscillating arm and movable on axes parallel with that of the said arm, pins carried by the bell-cranks and being adapted to move across the paths of movement of the oscillating pins in opposite directions all of said pins being parallel and adapted to receive the candy, and means for moving the bell-cranks and oscillating arm simultaneously, all combined substantially as described.

3. In a candy pulling machine; an oscillating arm capable of performing a part of a revolution about its axis, the arm having pins at opposite sides of the axis, bell-cranks having pins projected into the plane of the arm carried pins and adapted to move into and out of the paths of movement of the said pins in opposite directions, said bell-cranks being movable on parallel axes above and below that of the oscillating arm, means for revolving the oscillating arm and means for simultaneously moving the bell-cranks, all combined substantially as described.

4. In a candy pulling machine; an oscillating arm having pins on opposite sides and movable in a semi-circular path about the central axis of motion, vibrating bell-cranks movable in semi-circular paths in opposite directions on axes above and below the central oscillating arm each bell-crank having a pin adapted to bisect the path of movement of its co-acting oscillating pin twice in one vibration, and means for vibrating the bell-cranks and revolving the arm simultaneously, all combined substantially as described.

5. In a candy pulling machine; an oscillating arm having forwardly extending pins on opposite sides of its axis of motion, a pinion secured to the back of the arm, a gear segment meshing with the pinion, bell-cranks revoluble on axes parallel to and above and below the axes of the oscillating arm, one arm of each bell-crank extending toward the said arm, pins on the ends of the bell-crank arms adapted to co-act with the pins on the oscillating arm said bell-crank pins bisecting the path of movement of the oscillating pins twice in one vibration, connections between the other arms of the bell-cranks, means for moving the bell-cranks in opposite directions and means for rotating the oscillating arm simultaneously, all combined substantially as described.

6. In a candy pulling machine; a bed-plate, a standard on said bed-plate, a shaft mounted centrally of the standard, bell-

cranks mounted above and below the central shaft, said bell-cranks having long arms extending into proximity with the central shaft and movable in opposite directions from each other, pins on the ends of the said bell-crank arms, a link connection between the short arms of the bell-cranks, a crank on the end of the lower bell-crank shaft, an oscillating bar mounted on the central shaft 10 said bar having pins on each side of the axis of motion, the paths of motion of the said pins being crossed by the bell-crank pins in their vibration, a pinion on the central shaft, a gear segment meshing with the pinion, the segment being loosely mounted 15 on the lower bell-crank shaft, and a motor device for moving the gear segment and the crank on the end of the lower bell-crank shaft, simultaneously, all combined substantially as described.

7. In a candy pulling machine; a bed-plate, a standard on said bed-plate, a shaft mounted centrally of the standard, bell-cranks mounted above and below the central 25 shaft, said bell-cranks having long arms extending into proximity with the central shaft and movable in opposite directions from each other, pins on the ends of the said bell-crank arms, a link connection between 30 the short arms of the bell-cranks, a crank on the end of the lower bell-crank shaft, an oscillating bar mounted on the central shaft said bar having pins on each side of the axis 35 of motion, the paths of motion of the said pins being crossed by the bell-crank pins in their vibration, a pinion on the central shaft, a gear segment meshing with the pinion, the segment being loosely mounted on the lower bell-crank shaft, and a motor device for 40 moving the gear segment and the crank on the end of the lower bell-crank shaft, simultaneously, said motor device comprising a drive and driven shaft, intermediate gears, cranks on the ends of the driven shaft, a 45 connecting rod between the crank at one side and the crank on the bell-crank shaft and another connecting rod between the other crank on the driven shaft and the gear-segment.

50 8. The process of working candy consisting of revolving the mass in one direction a part of the time; intercepting and deflecting each end of the mass into the same direction, reversing the rotation of the body of the mass, and continuing the deflection of the ends in the first named direction.

9. The process of working candy and the like consisting of revolving the mass in one direction a part of the time; intercepting 60 and folding each end under the body of the mass in the same direction, reversing the direction of rotation of the body of the mass,

and continuing the deflection of the ends in the first named direction.

10. The process of working candy and the 65 like consisting of revolving the mass in one direction a part of the time; intercepting and folding opposite ends under the body of the mass in opposite directions from each other, reversing the direction of rotation of 70 the body of the mass, and continuing the deflection of the ends in the first named directions to form strands.

11. The process of working candy and the 75 like consisting of revolving the mass in one direction a part of the time; intercepting and folding opposite ends under the body of the mass in opposite directions from each other, reversing the direction of rotation of 80 the body of the mass, continuing the deflection of the ends in the first named directions to form strands, bringing the deflected strands into one mass and reversing the direction of the mass.

12. The process of working candy and the 85 like consisting of rotating the mass in one direction a part of the time; intercepting and folding opposite ends under the body of the mass in the direction of rotation of the ends of the mass but in opposite directions 90 from each other, reversing the rotation of the body of the mass while continuing the deflection of the ends to separate the mass into strands, bringing the strands together, reversing the rotation of mass, intercepting and folding under opposite ends 95 of the mass in directions opposite to those in the first-named instance.

13. In a candy pulling machine; an oscillating arm having pins on opposite sides of 100 its axis of motion, bell-cranks located radially of the oscillating arm, pins carried by the bell-cranks and being adapted to move in opposite directions across the paths of movement of the oscillating arm pins, and 105 means for moving the bell-cranks and oscillating arm, all combined substantially as described.

14. In a candy pulling machine; an oscillating arm having pins on opposite sides of 110 its axis of motion, bell-cranks located at each side of the oscillating arm and movable on axes parallel with that of the said arm, pins carried by the bell-cranks and being adapted to move across the paths of movement of the oscillating pins, said pins being adapted to receive the candy, and means for moving the bell-cranks and oscillating arm simultaneously, all combined substantially 115 as described.

JOHN M. HOWARTH.
